FIG. 3.

FRANK R. STEELY, INVENTOR

BY *Ed. Nell*

ATTORNEY

UNITED STATES PATENT OFFICE.

FRANK R. STEELY, OF HAMBURG, PENNSYLVANIA.

ELEVATOR.

1,159,809.

Patented Nov. 9, 1915.

Application filed May 6, 1915. Serial No. 26,208.

To all whom it may concern:

Be it known that I, FRANK R. STEELY, a citizen of the United States, residing at Hamburg, in the county of Berks and State 5 of Pennsylvania, have invented certain new and useful Improvements in Elevators, of which the following is a specification.

My invention relates particularly to refrigerators of the class which resemble a 10 "dumb waiter" and which are commonly known as disappearing refrigerators, and is especially directed to the mechanism whereby the refrigerator body is raised and lowered and maintained in its respective positions.

The principal objects of my invention are to provide a refrigerator of the class described, with means tending to thrust the cage or body upwardly through the floor, 20 to provide means for retaining said cage or body in its position beneath the floor, and to provide means to release said retaining means.

Other objects of my invention are to provide a refrigerator of the class described with shock absorbing mechanism which is effective at the termination of either the upward or downward movement of the cage or body, and to provide guiding mechanism 30 wholly disposed beneath the floor for directing said cage or body vertically.

My invention comprehends a stationary guiding frame, for movably supporting the cage or body, having adjustable legs movable longitudinally to vary the length of said frame.

My invention also includes all of the various novel features of construction and arrangement hereinafter more definitely specified.

In the accompanying drawings Figure 1 is a side elevational view of a refrigerator conveniently embodying my invention; Fig. 2 is a front elevational view of the refrigerator shown in Fig. 1; and Fig. 3 is a plan view of the structure shown in Figs. 1 and 2, with the floor removed.

In said figures the cage or body 5 is mounted for vertical movement in the stationary frame comprising the standards 6, 7 and 8 disposed upon opposite sides thereof, the standards 6 and 7 being connected by the transverse tie 9 and the standards 7 and 8 being connected by the transverse tie 10 55 at their lower ends.

The upper ends of the standards 6, 7 and 8 at the respectively opposite sides of the cage or body 5 are connected at their upper ends by the rectangular housing adjacent to the under surface of the floor 12, and comprising the front and rear walls 13 and 14 and side walls 15, and arranged to be disposed between joists 16.

The cage or body 5 is supported upon the cross-bar 17 which is carried by the cords 65 or chains 18 which are respectively attached to its opposite ends and which pass over sheaves 19, mounted in suitable bearings 20 on the side walls 15, and have their ends connected with suitable weights 21 which are 70 mounted to slide up and down between the standards 7 and 8.

The standards 7 and 8 are provided in their opposed faces with grooves 22 and 23 respectively which serve as guides for the 75 lugs 25 on the weights 21.

The cage or body 5 is provided upon its opposite sides, near the front, with vertically extending rails or ribs 26 which pass through the guides 27 on the respective 80 standards 6 and coöperate therewith to maintain the vertical position of said cage or body 5 as it moves up or down, and is also provided with rollers 28 arranged to traverse the opposed faces of the standards 6. 85

The cage or body 5 carries the transverse bar 29 having the vertically disposed rods 30 which loosely extend through the transversely disposed bars 31 and 32 and have 90 heads 33 for retaining the bar 32 thereon. The bars 31 and 32 are normally separated by spiral springs 35 which encircle the respective rods 30, and extend somewhat beyond the ends of the bar 29 so that the bar 95 31 may engage the lower edge of the side wall 15 in the upward movement of said cage, and the bar 32 may engage the upper edge of the stops 36, projecting inwardly from the standards 6 as best shown in Fig. 100 1, in the downward movement of said cage.

The cage or body 5 is provided with a cap 37 which is preferably rectangular to fit a similar opening 39 in the floor 12, and said cage is normally retained in the position beneath the floor, as shown in the drawings by the tripping mechanism comprising the detent hooks 40 which engage the respective cleats 41 upon the opposite sides of the cage 5 as best shown in Figs. 2 and 3, and which 110

are pivotally supported in suitable bearing frames 42 respectively secured to the inner faces of the side walls 15 of the housing.

The detent hooks 40 are normally forced 5 into engagement with the cleats 41 by the springs 43, best shown in Fig. 3, and are arranged to be withdrawn therefrom by the bell-crank-levers 45 which are pivoted on the bearing frames 42 and which have one 10 arm engaged in a suitably provided aperture in said detent hooks, and the other arm connected by the link 46 with the rocker arm 47 of the rock shaft 49.

The rock shaft 49 is mounted to rock in 15 the bearings 50 on the rear wall 14 of the housing and is provided with rocker arms 51, either of which may be connected by the cord or chain 52 with the foot treadle 53, by passing through said wall 14 and around 20 the sheave 55 which is mounted in the bearing frame 56 on the joist or other suitable support 57.

It will be observed that the treadle 53 is centrally pivoted in the bearing 58 within 25 the shield 59 and has the foot piece 60 so that when the operator presses upon said foot piece the tail 61 of the treadle will be raised and the rock shaft 49 rocked in its bearings whereby the bell-crank-levers 30 through their connection with the rocker arms 47 are rocked to effect the movement of the detent hooks 40 in opposition to their respective springs and thereby release them from the cleats 41. When thus released the 35 cage or body 5 is shot upwardly through the opening 39 in the floor 12 by the weights 21 which descend between their respective guides comprising the standards 7 and 8, until the bar 31 engages the under edge of 40 the walls 15 of the housing which tends to

compress the shock absorbing springs 35 and arrest the further movement of said cage.

In order that the stationary frame may be readily adaptable to varying distances 45 between the floors, the standards 6 and 8 may be provided with adjustable extension legs 63 and 65 each having a slot 66 through which the stud bolts 67 having the nuts 68 and washers 69 extend, thus it will be seen 50 that by loosening the nuts 68 said legs may be longitudinally shifted into any vertical position as shown for instance in dot and dash lines in Figs. 1 and 2.

The cage or body 5 may be conveniently 55 provided with a plurality of doors 70 and 71 in the front, while the sides and back may be provided with openings 72 provided with reticulated fabric 73 as shown in Fig. 1.

I do not desire to limit my invention to 60 the precise details of construction and arrangement herein set forth, as it is obvious that various modifications may be made therein without departing from the essential features of my invention as defined in 65 the appended claim.

Having thus described my invention, I claim:—

In a lift comprising a reciprocatory cage arranged to rise and fall through the floor, 70 the combination with a stationary frame, of a cage movable in said frame and having depending rods provided with heads at their free ends, cross-bars loosely carried by said rods, and springs between said cross- 75 bars tending to force one upwardly and the other downwardly.

In testimony whereof I affix my signature.

FRANK R. STEELY.
